UNITED STATES PATENT OFFICE.

EWALD SCHEUNERT, OF SILVER CREEK, WISCONSIN.

SILO ELEVATOR.

Application filed September 30, 1922. Serial No. 591,507.

To all whom it may concern:

Be it known that I, EWALD SCHEUNERT, a citizen of the United States, and resident of Silver Creek, in the county of Sheboygan, and State of Wisconsin, have invented certain new and useful Improvements in Silo Elevators; and I do hereby declare that the following is a full, and exact description thereof.

10 This invention relates to silo elevators and is particularly directed to an elevator adapted for manual operation.

In silos as heretofore constructed, it has been the practice to provide a chute down 15 which the ensilage is thrown, and to provide a ladder within the chute so that the operator may climb into the upper portion of the silo. These ladders soon become extremely 20 slippery and afford an unsafe footing, resulting in frequent accidents.

This invention is designed to overcome the above noted defects, and to provide an elevating apparatus adapted to raise the operator to the desired position without, however 25 unnecessarily complicating the construction of the silo.

Objects of this invention are to provide an elevator adapted to travel in the usual silo chute down which ensilage is thrown, to provide an elevator which is inherently safe and 30 may be operated by an unskilled person, to provide an elevator which may be folded against the side of the chute when not in use so as to leave the chute unobstructed, and to 35 provide an elevator which is automatic in its locking action.

Further objects are to provide an elevator which may be constructed in a cheap and simple manner, which may be applied to 40 silos with a minimum of alterations of such silos, and to provide an elevator of sturdy and rugged design.

An embodiment of the invention is shown in the accompanying drawings, in which:—

45 Figure 1 is a vertical sectional view thru a silo chute showing the elevator in its lowest position.

Figure 2 is a front view of the elevator.

50 Figure 3 is a transverse sectional view thru the chute and a portion of the silo, and illustrating a relative position occupied by the elevator.

55 Figure 4 a vertical sectional view thru the chute showing the elevator in folded position.

Referring more particularly to the draw-

ing, it will be seen that the silo 1 is provided with the usual chute, or passageway, 2, and that such passage way is separated from the main silo body by removably positioned 60 boards 3. Upon one of the walls, such as the side wall 4 of the chute, a pair of brackets 5 and 6 are secured and carry between them an elongated chain 7, such chain paralleling the side wall 4 and being spaced therefrom a slight distance.

The elevator proper, or car, comprises a back portion 8 which is positioned between the wall 4 and the chain 7, and has pivoted adjacent its lower end, a base, or floor, 9. 70 A link 10 is pivotally joined to each of the outer corners of the base portion 9, and has its upper end pivotally joined to an intermediate link 11. This intermediate link, at its upper end, is joined to a link 12 pivoted at 75 13 to the upper portion of the back 8 of the elevator. Adjacent the upper portion of the back 8, a two part housing 14 is secured and projects forwardly from such back. This casing houses a sprocket wheel 15, which is 80 rigidly secured to a transverse shaft 16, such shaft having its end projecting outwardly beyond the casing. A pair of operating cranks 17 and 18 are rigidly secured to the shaft externally of the casing, as may be 85 seen from Figures 2 and 4.

The sprocket wheel is provided with rugged teeth 19 which engage in the relatively heavy chain 17, such chain being constrained to move at all times adjacent 90 the sprocket wheel by means of a pair of enlarged bearing surfaces 20 and 21 formed upon the back portion 8 (see Figure 1). The upper portion of the back 8 is provided with an eyelet 22, to which is attached a 95 counter weight cable 23. This cable passes over a pulley 24 adjacent the upper portion of the chute, and is secured to a counter weight 25 mounted externally of the chute. If desired a suitable housing 26 may 100 be provided for the counter weight.

The elevator is equipped with a safety locking device which comprises a pawl, or detent, 27, pivotally mounted at 28 upon the body portion, and provided with a rigid 105 outwardly extending arm 29. This pawl is adapted to engage the chain 7 between successive links and may, if desired, fit within a recessed portion formed in the enlarged part 21 of the back 8, as shown in Figure 1. 110 A convenient way of constructing this pawl, or detent, is shown in Figure 2, from which

it will be seen that the pawl 27 is provided with an operating, or rock, shaft 30, which carries adjacent its outer end the rigid arm 29. This arm 29 is connected by means of 5 a link 31 with the outer end 32 of a foot lever pivoted at 33 to the back of the elevator. The foot lever is moved into the position shown in Figure 2 with the pawl in locking engagement, under normal condition, by means of a spring 34. However, the pawl may be moved out of engaged position by stepping upon the foot receiving portion 10 35 of the foot lever. When this is done, the link 31 moves upwardly, thereby rocking the 15 detent, or pawl, 27 out of engagement with the chain 7.

The operation of the device is as follows:—The operator steps upon the platform 9 and releases the pawl 27 by placing his foot upon the foot receiving portion 35 of the lever. At the same time he grasps the cranks 17 and 18 and rotates them, thereby causing the sprocket wheel to travel upwardly along the chain 7, which, in turn, elevates the apparatus. If at any time he inadvertently removes his foot from the lever, as for example under fortuitous conditions, the lever will immediately move to the position shown in Figure 2, thereby causing the detent to lock the device against downward motion. When the elevator has reached its upper limit of travel, the operator removes his foot from the lever and the device is locked in position. Thereafter he may step into the upper portion of the silo and fold the elevator into the position shown in Figure 4 by pulling the pivotal portion 36 of the levers 11 and 12 outwardly and forcing the platform, or base, 9 upwardly into the position shown. In this way the elevator is collapsed and caused to occupy a very small space with the platform 9 adjacent the wall 4—the supporting levers 11 and 12 being out of the way adjacent the front and rear walls of the silo, thus leaving the chute free and unobstructed.

It will be seen that a manually operable elevator has been provided for a silo in such a manner that the usual chute may be employed as the elevator shaft, in which a collapsible elevator is provided so as to leave the chute unobstructed when the elevator is not in use, and in which adequate safety devices are provided.

It will further be seen that an extremely simple and rugged elevator has been provided which may be simply and easily operated by an unskilled person, and which is composed of a relatively small number of parts.

Although one form of the invention has been described to considerable detail, it is to be understood that the invention may be embodied in several different forms, and is therefore to be limited only as set forth in the appended claims. 65

I claim:

1. In combination, a silo having an ensilage chute, and a collapsible elevator located and adapted to travel within said chute. 70

2. In combination, a silo having a walled ensilage chute, a chain secured adjacent its upper and lower ends to one of the walls of said chute, a car adapted to travel along said chain, a sprocket wheel carried by said car and operatively engaging said chain, a pair of cranks rigidly associated with said sprocket wheel, a car including a platform, means adapted to hold said platform in an extended position or to permit said platform to be rocked upwardly into a position closely adjacent the wall of said ensilage chute. 80

3. An elevator comprising a vertical chain secured adjacent its lower and upper ends in a fixed position, a car adapted to travel along said chain, said car comprising a back portion mounted to the rear of said chain, a sprocket wheel mounted in front of said chain and operably engaging it, manual means for driving said wheel, a platform having one end pivoted to said back portion, a pair of links connecting the upper portion of said back with the outer portion of said platform and permitting said platform to occupy an extended position or a position adjacent said back, a detent carried by said car and normally engaging said chain to lock the car in fixed position, a foot lever operatively connected to said detent, and resilient means biasing said detent to locking position. 85

4. In combination, a silo having an ensilage chute, and a collapsible elevator located and adapted to travel within said chute, a chain secured adjacent its upper and lower ends to one of the walls of said chute, a car adapted to travel along said chain, a sprocket wheel carried by said car and operatively engaging said chain, a pair of cranks rigidly associated with said sprocket wheel, a car including a platform, means adapted to hold said platform in an extended position or to permit said platform to be rocked upwardly into a position closely adjacent the wall of said ensilage chute, a back portion mounted to the rear of said chain, a sprocket wheel mounted in front of said chain and operably engaging it, manual means for driving said wheel, a platform having one end pivoted to said back portion, a pair of links connecting the upper portion of said back with the outer portion of said platform and permitting said platform to occupy an extended position or a position adjacent said back, a detent carried by said car and normally engaging said chain to lock the car in fixed position, a foot lever operatively connected to said detent, and resilient means biasing said detent to locking position. 90

5. An elevator comprising a vertical chain secured adjacent its lower and upper ends in a fixed position, a car adapted to travel along said chain, said car comprising a back portion mounted to the rear of said chain, a sprocket wheel mounted in front of said chain and operably engaging it, manual means for driving said wheel, a platform having one end pivoted to said back portion, a pair of links connecting the upper portion of said back with the outer portion of said platform and permitting said platform to occupy an extended position or a position adjacent said back, a detent carried by said car and normally engaging said chain to lock the car in fixed position, a foot lever operatively connected to said detent, and resilient means biasing said detent to locking position. 95

6. An elevator comprising a vertical chain secured adjacent its lower and upper ends in a fixed position, a car adapted to travel along said chain, said car comprising a back portion mounted to the rear of said chain, a sprocket wheel mounted in front of said chain and operably engaging it, manual means for driving said wheel, a platform having one end pivoted to said back portion, a pair of links connecting the upper portion of said back with the outer portion of said platform and permitting said platform to occupy an extended position or a position adjacent said back, a detent carried by said car and normally engaging said chain to lock the car in fixed position, a foot lever operatively connected to said detent, and resilient means biasing said detent to locking position. 100

In testimony that I claim the foregoing I ¹⁰⁵ have hereunto set my hand at Silver Creek, in the county of Sheboygan and State of Wisconsin.

EWALD SCHEUNERT.
